UNITED STATES PATENT OFFICE.

CHRISTIAN M. LAURITZEN, OF CHICAGO, AND WILLIAM H. VOGEL, OF HIGHLAND PARK, ILLINOIS, ASSIGNORS TO RAYMOND BROTHERS IMPACT PULVERIZER CO., OF CHICAGO, ILLINOIS, A CORPORATION OF ILLINOIS.

PULVERIZING MILL.

Application filed March 2, 1925. Serial No. 12,639.

To all whom it may concern:

Be it known that we, CHRISTIAN M. LAURITZEN and WILLIAM H. VOGEL, citizens of the United States, residing at Chicago and Highland Park, in the county of Cook and State of Illinois, respectively, have invented certain new and useful Improvements in Pulverizing Mills, of which the following is a specification.

10 This invention relates to means for pulverizing fuel, and more particularly to improvements in a pulverizing mill of the impact type, in which a plurality of rotary hammers operate within a substantially cylindrical beater chamber.

One object of this invention is to provide improved means for guiding the material to be pulverized into the path of the beaters or hammers, and for directing back into the path of these hammers coarse material, or material not sufficiently pulverized, to insure a more evenly proportioned and constant output of the pulverized material, and more economical operation of the mill.

25 A further object is to provide improved means for adjusting the fineness of the pulverized material produced, such means being accessible for adjustment from outside the mill, without necessarily stopping the 20 operation of the mill.

30 A further object is to provide means adjustable from outside the beater chamber for compensating for wear of the beater hammers, whereby the desired fineness of 35 pulverization may be maintained even after such wear takes place.

Other objects and advantages of this invention will be apparent from the following detailed description of certain approved 40 forms of the apparatus.

In the accompanying drawing:

Fig. 1 is a central vertical longitudinal section, partly in elevation, through the main portions of the mill.

45 Fig. 2 is a transverse sectional view, taken substantially on the line 2—2 of Fig. 1.

Fig. 3 is a detail longitudinal section corresponding to the lower portion of Fig. 1, showing a modified form of the directing 50 rings.

Fig. 4 is a view similar to Fig. 1, showing another modification.

Fig. 5 is a similar view, partly broken away, of still another modification.

Fig. 6 is a transverse section, corresponding to the right-hand portion of Fig. 2, showing a peripheral inlet opening.

The mill, as here shown, (referring first to Figs. 1 and 2), is of the well known impact type, and comprises a feeding compartment 1, a beater chamber 2 in which the pulverization process takes place, and a fan chamber 3. A horizontal shaft 4 extends centrally through the substantially cylindrical chambers 2 and 3, and is rotatably supported at its ends, outside of the chambers, in bearings 5 and 6. One projecting end 7 of shaft 4 is connected with an electric motor, or other suitable driving means. Within the beater chamber 2, the pulverizing mechanism 8, hereinafter more specifically described, is fixedly mounted on rotary shaft 4, and a fan 9 is similarly mounted on shaft 4 within the fan chamber 3.

The material to be pulverized is maintained within a hopper or other storage receptacle, the lower end of which is indicated at 10, and the flow of material from this receptacle into feeding compartment 1 is regulated by the slide valve 11. Below the valve 11, a pocketed feed wheel 12 is mounted on a shaft 13 to rotate in a clockwise direction, Fig. 1, and thus steadily feeds measured quantities of the material into the lower portion of feeding compartment 1 and thence through inlet opening 14 into the inlet end of beater chamber 2. The shaft 13 is intermittently and adjustably driven at a slow speed, by a mechanism not shown, from the shaft 15 in the lower portion of the mill housing, which shaft 15 is driven through suitable reduction gearing and the belt 16 from the main rotary shaft 4.

The pulverizing mechanism 8 comprises a plurality (here shown as three duplicate radial series), of beaters or hammers 17, pivotally mounted at their inner ends 18 for limited swinging movement, within a frame or spider composed of a series of plates or discs 19 keyed on shaft 4, spaced apart by rings 20, and clamped in assembled position with the rings 20 upon shaft 4 between collar 21 on shaft 4 and an adjustable nut 22 on said shaft. Suitable liner members (not

all here shown), are arranged about the path of travel of hammers 17 and within the enclosing outer wall of the beater chamber 2, and the material is pulverized partially by the impact of the hammers 17, and partly by being projected by centrifugal force against the liner members.

The fan 9 withdraws the pulverized material suspended in air, from beater chamber 2 through the outlet opening 23 into fan chamber 3, and projects this fuel laden air through conduit 24 to a suitable storage bin or directly to the burners where it is consumed. Air is supplied to the beater chamber 2, from the inlet pipe 25 and through feeding compartment 1, and additional air may be supplied to fan chamber 3 through an adjustable inlet 26.

In connection with a mill of this type, difficulty has been experienced in maintaining a constant distribution of the material to be pulverized in the path of the hammers 17 so that all of the hammers will be effective, and consequently in maintaining a constant output and a constant working load for the mill. It has been found that some of the material fed into the beating zone through inlet opening 14, will be thrown out by the outer rows of hammers and will accumulate 30 in the lower corners of the beater chamber as at 27.

The hammers 17 will operate most effectively if the clearance between these hammers and the surrounding liner-members is 35 comparatively small, but with such a small clearance it is particularly difficult to provide a constant feed of material to all of the hammers and to maintain this material in the narrow beating zone until properly pulverized. To overcome this difficulty we have provided deflecting means at the sides of the zone in which the hammers 17 rotate and operate, against which the material thrown out by the side rows of hammers will impact and be directed back horizontally into the path of the hammers and be subjected to further pulverization.

Accordingly, we have provided an inclined directing plate 28, which preferably 50 is a part of a continuous ring or annular member extending clear around one end of the cylindrical chamber 2. The plate 28 preferably inclines inwardly toward the hammers, and outwardly from shaft 4 at an 55 angle of about 45°, with one edge extending substantially in line with the path of travel of the first row of hammers 17. As shown in Fig. 1, the directing plate or ring 28, is formed integrally at one end of a liner plate or ring 29, which extends substantially 60 across the peripheral portion of chamber 2. As the hammers 17 wear away, it is desirable to adjust the plate 28 toward the hammers to compensate for this wear. This may be 65 done by means of inserting suitable shims

30, as indicated in Fig. 1, or the plate or ring 28 may be provided with adjusting screws 31 extending through the adjacent wall of the mill housing as indicated in Fig. 5.

At the other side of the hammers 17, within the chamber 2, is positioned a similar inclined deflecting ring 32, which is adjustable from outside of the mill housing by means of screws 33. By suitably turning the screws 75 33, the ring 32 may be moved toward or from the path of travel of the adjacent annular row of hammers 17. The plates 28 and 32 serve to direct the coarse or unpulverized material thrown thereagainst by 80 centrifugal force back into the path of travel of the beaters or hammers 17 thereby subjecting the material again to the pulverizing operation, and increasing the fineness of the product delivered to the fan chamber 85 3. The closer the rings 28 and 32 are adjusted to the path of travel of the hammers 17, the longer the material will be subjected to the grinding operation, and the finer the grinding. By properly adjusting the relative positions of the rings with respect to the path of travel of the hammers 17, the fineness of the material produced by the mill may be increased or diminished within certain limits. The plates or rings 28 and 32 90 will also be adjusted toward the hammers 17 to compensate for wear of the hammers, thus maintaining the efficiency of the mill, even after considerable of such wear takes place.

When these deflecting members are used as hereinabove described, the operation of the mill is steadier, less power is required to operate the mill, and a product of more even and constant quality and fineness is delivered from the mill through the conduit 100 24. It is also possible to operate the mill with a much smaller clearance between the outer ends of the hammers 17 and the liner plates in the chamber 2, thus increasing the efficiency of the mill and the uniformity and 110 fineness of the material produced therein.

Preferably a recess or air-pocket 34 will be provided at the top of chamber 2 beyond the beating zone of hammers 17. This recess functions to interrupt the continuity of 115 travel of the material through the mill, this retarding action increasing the efficiency of the grinding operation. This recess increases the air capacity of the mill and enables the mill to be operated with a smaller 120 fan, or the same fan will deliver more air through the mill than was formerly the case. The mill will also be able to carry a heavier load without "choking" or becoming clogged by an accumulation of stagnant material.

In the modification shown in Fig. 3, the two deflecting plates or rings 28 and 32 are secured to, or made integral with an annular connecting member 35, and this assembly is adjustable toward one side or the 125 130

other of chamber 2 by means of the adjusting screw 36 and 37 mounted in the chamber walls and bearing against the opposite sides of the rings.

- 5 In the modification illustrated in Fig. 4, the deflecting ring assembly (which may be of the form shown in Fig. 3) is fixedly mounted within that portion 38 of the mill housing which encloses the chamber 10 2, and this casing portion 38 is bodily adjustable laterally to carry the rings 28 and 32 toward or from the hammers as desired. As shown, the walls 39 at one end of casing 38 surround and are slidable 15 along a cylindrical extension 40 of the fixed housing 41 at the inlet end of the mill. The conical outlet portion 42 of casing 38 has a cylindrical extension or neck 43 slidable laterally within an opening 44 20 in the end wall 45 of the fan chamber 3. Casing section 38 is adjusted laterally, and held in adjusted position by any suitable means such as adjusting screws 46 and 47, mounted in the fixed portions of the mill 25 housing, and connected at their inner ends with casing 38. Obviously, one of the rings 28 or 32 might be made as a separate unit and adjustable toward or from the other ring (as in Fig. 1), to compensate for wear 30 of the hammers.

As an alternative to the form of the invention just described, the entire casing might be fixed, but the shaft 4, and the hammer assembly carried thereby could be bodily 35 adjusted laterally within the casing to carry the hammers toward or from either ring 28 or 32. This could be done by adjusting the shaft 4 in either direction through bearings 5 and 6 by any suitable thrust means, not 40 here illustrated.

In the form of the invention shown in Fig. 5, a regulator or "whizzer" 48 is mounted on shaft 4 adjacent the outlet opening 23. This rotary regulator comprises a series of 45 radially disposed plates 49, the outer ends of which are preferably inclined as at 50 and positioned to travel within a short distance of the inner face of the conical ring 51, which forms the inner wall of the outlet 55 23 at this point. The action of this regulator is to reduce very materially the amount of coarse material passing through outlet 23 into the fan chamber. This regulator acts as a fan for continuing the rotary movement of the contents of beater chamber 2 about the axis of shaft 4, and by centrifugal force throws the coarser material against the diagonally disposed face of ring 51 from 60 which it is thrown back into the beating zone in chamber 2. The retarding action of this regulator may be varied by adjusting it along shaft 4 toward or from the conical ring 51. Since this "whizzer" 48 performs much the same function as ring 32, previously described, this ring is omitted in the apparatus

shown in Fig. 5 and only the ring 28 at the inlet end of the chamber 2 is used. This ring 28 and the whizzer 48 cooperate to keep the coarse material within the beating zone until completely pulverized. Of course, 70 the ring 32 could also be used in this form of the apparatus, or conversely the whizzer 48 could be used in the forms of the apparatus shown in Figs. 1 and 4. In such cases the deflecting ring 32 and whizzer 75 48 will act to supplement one another and maintain the material within the mill until complete pulverization is accomplished.

It is not essential that the material be fed 80 into the beater chamber 2 at the end heretofore designated the "inlet end" as shown in Figs. 1, 4 and 5. In larger mills it might be desirable to feed the material to the mill at some other point, for example at the top or at one side of the peripheral portion of 85 the mill as indicated in Fig. 6. Here the feed compartment 52, and the measuring devices therein, may be of the form shown in Fig. 1, and the material is fed tangentially through opening 53 directly into the 90 beating zone of hammers 17. In this form of the invention, as in all of the forms previously described, the coarser material that tends to escape from the action of the hammers at either side is projected by centrifugal force against one or the other of the 95 rings 28 or 32 and thence thrown back into the path of the hammers. Only the completely pulverized material is too light to be so treated, and floats out through opening 23 upon the stream of air drawn there-through by fan 9.

We claim:

1. A pulverizing mill comprising a substantially cylindrical beater chamber, a plurality of hammers mounted to revolve within the chamber, about the axis of the chamber, and annular means mounted within the chamber adjacent the sides of the zone within which the hammers operate, for directing material thrown thereagainst, back into the path of the hammers.

2. A pulverizing mill comprising a beater chamber, a plurality of hammers mounted to move about an axis in this chamber, the material to be pulverized being fed into the chamber at one location and the pulverized material withdrawn at another, and deflecting rings mounted within the chamber adjacent the zone in which the hammers operate for directing unpulverized material into the path of the hammers.

3. A pulverizing mill comprising a beater chamber, a plurality of hammers mounted to move about an axle in this chamber, the material to be pulverized being fed into the chamber at one location and the pulverized material withdrawn at another, and annular means having impact faces inclined to the planes of movement of the hammers

mounted within the chamber adjacent the zone in which the hammers operate for directing the unpulverized material into the path of the hammers.

5. A pulverizing mill comprising a beater chamber, a plurality of hammers mounted to move about an axis in this chamber, the material to be pulverized being fed into the chamber at one location and the pulverized material withdrawn at another, and deflecting rings having impact faces inclined to the planes of movement of the hammers mounted within the chamber adjacent the zone in which the hammers operate for directing unpulverized material into the path of the hammers.

10. A pulverizing mill comprising a beater chamber, a plurality of hammers mounted to move about an axis in this chamber, the material to be pulverized being fed into the chamber at one location and the pulverized material withdrawn at another, and deflecting rings mounted within the chamber adjacent the zone in which the hammers operate and adjustable toward and from the hammers for directing unpulverized material into the path of the hammers.

15. A pulverizing mill comprising a beater chamber, a plurality of hammers mounted to move about an axis in this chamber, the material to be pulverized being fed into the chamber at one location and the pulverized material withdrawn at another, means mounted within the chamber adjacent the zone in which the hammers operate for directing unpulverized material into the path of the hammers, and means for varying the clearance between the directing means and the hammers moving adjacent thereto.

20. A pulverizing mill comprising a beater chamber, a plurality of hammers mounted to move about an axis in this chamber, the material to be pulverized being fed into the chamber at one location and the pulverized material withdrawn at another, and annular means mounted within the chamber adjacent the sides of the zone in which the hammers operate for deflecting material thrown thereagainst by centrifugal force, back into the path of the hammers.

25. A pulverizing mill comprising a beater chamber, a plurality of hammers mounted to move about an axis in this chamber, the material to be pulverized being fed into the chamber at one location and the pulverized material withdrawn at another, and annular members having inclined impact faces mounted within the chamber adjacent the sides of the zone in which the hammers operate for deflecting material thrown thereagainst by centrifugal force, back into the path of the hammers.

30. A pulverizing mill comprising a beater chamber, a plurality of hammers mounted to move about an axis in this chamber, the

material to be pulverized being fed into the chamber at one location and the pulverized material withdrawn at another, annular members having inclined impact faces mounted within the chamber adjacent the 70 sides of the zone in which the hammers operate for deflecting material thrown thereagainst by centrifugal force, back into the path of the hammers, and means for adjusting the impact members toward or from the 75 hammers.

35. A pulverizing mill comprising a beater chamber, a plurality of hammers mounted to move about an axis in this chamber, means to feed air and material to be pulverized into the chamber, and means for withdrawing the air and pulverized material carried thereby, the chamber being provided with a recess or air-pocket in its peripheral portion beyond the path of travel of the 85 hammers.

40. A pulverizing mill comprising a beater chamber, a plurality of hammers mounted to move about an axis in this chamber, means to feed air and material to be pulverized into the chamber, and means for withdrawing the air and pulverized material carried thereby, the chamber being formed with a small peripheral clearance beyond the path of travel of the hammers, which clearance is enlarged at one location to form an air-pocket.

45. A pulverizing mill comprising a beater chamber, a plurality of hammers mounted to move about an axis in this chamber, the material to be pulverized being fed in at one end of the chamber and withdrawn at the other end, and an annular deflecting member mounted in the chamber at the inlet end for guiding the material into the path 100 of travel of the hammers.

50. A pulverizing mill comprising a beater chamber, a plurality of hammers mounted to move about an axis in said chamber, the material to be pulverized being fed in at one end of the chamber and withdrawn at the other end, and annular deflecting plate, having an impact face inclined toward the path of travel of the hammers, mounted in the inlet end of the beater chamber.

55. A pulverizing mill comprising a beater chamber, a plurality of hammers mounted to move about an axis in said chamber, the material to be pulverized being fed in at one end of the chamber and withdrawn at the other end, an annular deflecting plate having an impact surface inclined toward the path of travel of the hammers, mounted in the inlet end of the beater chamber, and means for adjusting the plate toward or from the hammers.

60. A pulverizing mill comprising a beater chamber, a plurality of hammers mounted to move about an axis in said chamber, means for feeding in material to be pulverized

- ized at one end of said chamber, means for withdrawing the pulverized material at the other end of the chamber, and an adjustably mounted inclined deflecting member filling the lower corner of the chamber at the inlet side for guiding the material into the path of the hammers.
16. A pulverizing mill comprising a beater chamber, a plurality of hammers mounted to move about an axis in said chamber, the material to be pulverized being fed in at one end of the chamber and withdrawn at the other end, deflecting plates, inclined downwardly and toward the path of travel of the hammers, mounted in the respective ends of the beater chamber, and means for adjusting the plates toward or from the hammers.
17. A pulverizing mill comprising a beater chamber, a plurality of hammers, mounted to move about an axis in said chamber, the material to be pulverized being fed in at one end of the chamber, means for withdrawing the pulverized material at the other end of the chamber, and an inclined deflecting member adjustably mounted in the outlet end of the chamber adjacent the path of travel of the hammers.
18. A pulverizing mill comprising a beater chamber, a plurality of hammers mounted to move about an axis in said chamber, means for feeding material to be pulverized into said chamber, the chamber having an outlet at one end thereof, means for withdrawing the pulverized material suspended in air through this outlet, and means adjustable from outside the chamber for regulating the flow of material through this outlet.
19. A pulverizing mill comprising a beater chamber, a plurality of hammers mounted to move about an axis in said chamber, means for feeding material to be pulverized into said chamber, the chamber having an outlet at one end thereof, means for withdrawing the pulverized material suspended in air through this outlet, and means adjustable from outside the chamber for retarding the flow of material through this outlet.
20. A pulverizing mill comprising a beater chamber, a plurality of hammers mounted to move about an axis in said chamber, means for feeding material to be pulverized into said chamber, the chamber having an outlet at one end thereof, means for withdrawing the pulverized material suspended in air through this outlet, and an inclined deflecting means mounted in the outlet end of the chamber.
21. A pulverizing mill comprising a beater chamber, a plurality of hammers mounted to move about an axis in said chamber, means for feeding material to be pulverized into said chamber, the chamber having an outlet at one end thereof, means for withdrawing the pulverized material suspended in air through this outlet, and an inclined deflecting means adjustably mounted in the outlet end of the chamber at one end of the chamber, means for withdrawing the pulverized material suspended in air through this outlet, and an inclined deflecting means adjustably mounted in the outlet end of the chamber.
22. A pulverizing mill comprising a beater chamber, a shaft extending therethrough, a plurality of hammers mounted on said shaft, means for feeding material to be pulverized into said chamber, the chamber having an outlet around the shaft at one end of the chamber, means for withdrawing the pulverized material suspended in air through this outlet, and an adjustable deflecting ring mounted in the outlet end of the chamber.
23. A pulverizing mill comprising a beater chamber, a shaft extending centrally therethrough, a plurality of hammers, mounted on the shaft, means for feeding material to be pulverized into the chamber, the chamber having an outlet around the shaft at one end of the chamber, a suction means for withdrawing the pulverized material suspended in air through this outlet, means adjacent the outlet for retarding the flow of material therethrough and directing this material back toward the hammers, and additional means in the chamber adjacent the path of travel of the hammers for directing unpulverized material into the path of the hammers.
24. A pulverizing mill comprising a beater chamber, a shaft extending centrally therethrough, a plurality of hammers mounted on the shaft, means for feeding material to be pulverized into the chamber, the chamber having an outlet around the shaft at the other end of the chamber, a suction means for withdrawing the pulverized material suspended in air through this outlet, means adjacent the outlet for retarding the flow of material therethrough and directing this material back toward the hammers, and additional means adjustably mounted in the chamber adjacent the path of travel of the hammers for directing unpulverized material into the path of the hammers.
25. A pulverizing mill comprising a beater chamber, a shaft extending centrally therethrough; a plurality of hammers mounted on the shaft, means for feeding material to be pulverized into the chamber, the chamber having an outlet around the shaft at one end of the chamber, a suction means for withdrawing the pulverized material suspended in air through this outlet, means adjacent the outlet for retarding the flow of material therethrough and directing this material back toward the hammers, and an annular member having an inclined impact face mounted in the chamber adjacent the path of travel of the hammers.
26. A pulverizing mill comprising a beater chamber, a shaft extending centrally therethrough, a plurality of hammers mounted on the shaft, means for feeding material to be

pulverized into the chamber, the chamber having an outlet around the shaft at one end of the chamber, a suction means for withdrawing the pulverized material suspended in air through this outlet, means adjacent the outlet for retarding the flow of material therethrough and directing the material back toward the hammers, and annular members having inclined impact faces adjustably mounted in the chamber adjacent each side of the path of travel of the hammers.

27. A pulverizing mill comprising a beater chamber, a plurality of hammers mounted to move about an axis in said chamber, means for feeding material to be pulverized into the chamber, means for withdrawing the pulverized material from the chamber, and inclined means in the ends of the chamber,

adjacent the path of travel of the hammers for directing material thrown thereagainst by centrifugal force back into the path of the hammers.

28. A pulverizing mill comprising a beater chamber, a plurality of hammers mounted to move about an axis in said chamber, means for feeding in material to be pulverized into the chamber, means for withdrawing the pulverized material from the chamber, and inclined means adjustably mounted in the ends of the chamber, adjacent the path of travel of the hammers for directing material thrown thereagainst by centrifugal force back into the path of the hammers.

CHRISTIAN M. LAURITZEN.
WILLIAM H. VOGEL.
